UNITED STATES PATENT OFFICE.

WILLIAM J. KREIMER, OF ST. LOUIS, MISSOURI.

AIR COMPRESSOR.

Application filed July 14, 1920. Serial No. 396,313.

To all whom it may concern:

Be it known that I, WILLIAM J. KREIMER, a citizen of the United States, residing at St. Louis, in the State of Missouri, have invented certain new and useful Improvements in Air Compressors, of which the following is a specification, reference being had to the accompanying drawings.

This invention relates to certain improvements in air compressors and has relation more particularly to a device of this general character, and it is an object of the invention to provide a novel and improved device of this general character whereby a supply of compressed air or other fluid may be readily obtained.

Furthermore, it is an object of the invention to provide a novel and improved device of this general character including a piston supported for rectilinear movement within a cylinder or compression chamber and wherein a rotatable member is provided to impart the requisite reciprocation to the piston.

A still further object of the invention is to provide a novel and improved device of this general character including a piston having rectilinear movement within a cylinder or compression chamber together with a member rotating in one direction and provided with means operatively engaged with the piston for imparting the requisite reciprocations thereto, and furthermore wherein said rotatable member is provided at its opposite end portions with reversely directed spirals or threads with which contacts a rock member carried by the extended portion of the rod for the piston, the intermediate portion of the rotatable member constituting a cam for coaction with the opposite end portions of the rock member whereby said rock member in proper sequence is caused to have the desired engagement with the spirals.

The invention consists in the details of construction and in the combination and arrangement of the several parts of my improved compressor whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the

better understood, I will now proceed to describe the same with reference to the accompanying drawings, wherein:

Figure 1 is a view in side elevation of a compressor constructed in accordance with an embodiment of my invention, a portion being broken away.

Figure 2 is a fragmentary view in top plan of the structure as illustrated in Figure 1.

Figure 3 is an enlarged fragmentary view partly in vertical section and partly in side elevation of the means for operating the reciprocating piston comprised in the air compressor with a portion of the cylinder or compression chamber associated with said piston.

Figure 4 is a fragmentary view partly in section and partly in elevation of the cylinder or compression chamber and the piston associated therewith and illustrating in detail the valves associated with said cylinder or chamber.

Figure 5 is a fragmentary view partly in plan and partly in longitudinal section taken through one of the lower valves as disclosed in Figure 4.

Figure 6 is a transverse sectional view taken substantially on the line 8—8 of Figure 3.

Figure 7 is a fragmentary transverse sectional view taken substantially on the line 9—9 of Figure 3.

Figure 8 is a fragmentary view partly in section and partly in elevation of the delivery end of one of the pipes or conduits leading from the compression cylinder or chamber to within the storage tank or reservoir, and

Figure 9 is an enlarged longitudinal vertical sectional view taken through the operating mechanism for the valves associated with the compression cylinder or chamber.

As disclosed in the accompanying drawings, R denotes a reservoir or tank and supported by the reservoir or tank R exteriorly thereof is a compression chamber or cylinder C in which is arranged for rectilinear movement a piston 51. Leading from the tank or reservoir R is a discharge pipe or conduit 10. Operatively engaged with the piston 51 is the rod 52 extending exteriorly of the cylinder or chamber C through the inner head 53 of said cylinder. The outer or exterior end portion of the rod 52 is engaged with a head 54. The head 54 has

sliding movement within a longitudinally disposed slot 55 provided in a table T and which table is operatively supported by the structure A. The slot 55 extends in the 5 same general direction as the direction of travel of the rod 52 and the marginal portions of the table T defining the slot 55 fit within the groove 56 provided in the side faces of the elongated flange or rib 57 depending from the head 54 and extending through the slot 55, whereby the head 54 is supported for reciprocatory movement in a fixed path of travel and whereby the requisite rectilinear movement is imparted to 10 the piston 51.

The inner longitudinal marginal portion of the table T is provided with a depending wall 58 arcuate in cross section as 15 illustrated in Figure 6 and which wall is provided with an outstanding flange 59 adapted to overlie the upper portion of the structure A and suitably anchored thereto, whereby the table T is maintained in applied position. The opposite ends of the 20 wall 58 are provided with the end plates 60 which serve as bearings for the shaft 61. The shaft 61 has its opposite end portions 25 extending outwardly of the end plates 60 and the extended portion of said shaft 61 adjacent the cylinder C has fixed thereto a gear 62 meshing with a gear 63 loose on the driving shaft 64 of the motor M and which 30 motor is preferably of an electrical type, although I do not wish to be understood as 35 limiting myself in this respect.

The gear 63 is provided with a clutch face 65 with which coacts the clutch member 66 mounted upon the shaft 64. The clutch member is adapted for rotation with the shaft 64 but capable of adjustment into or out of locking engagement with the clutch 40 face 65. The requisite operation of the clutch member 66 is under control of the upstanding rock arm 67 carried by the shaft 68 and which shaft 68 is rocked as required 45 through the instrumentality of the lever 69. By proper adjustment of the clutch member 66, the shaft 61 may be brought into driven connection with the shaft 64 when required or said shaft 61 permitted to rotate 50 independently of the shaft 64 when preferred.

Carried by the shaft 61 and snugly fitting 55 between the end plates 60 is a cylindrical member or drum D. The periphery of the member or drum D is provided with the reversely directed spiral channels or grooves 70 having their inner portions merging at substantially the longitudinal center of the member or drum D, the bases of said merging 60 portions of the grooves or channels 70 being gradually raised as at 71 to provide a lifting cam for a purpose to be hereinafter more particularly referred to.

The head 54 is provided in its under sur-

face with a longitudinally disposed recess or groove 72 and arranged within said groove or recess 72 is a rocking lever 73. The rocking lever 73 is pivotally supported as at 74 midway its length and the opposite 70 ends of said lever 73 are provided with the lugs or feet 75 adapted to ride within the spiral grooves or channels 70 of the member D, one of said lugs or feet 75 being raised or inoperative when the second lug or foot 75 is in working or operative position. The major length of the lever 73 is substantially equal to one-half of the length of the member or drum D so that when the head 54 has substantially reached its limit of movement 80 in one direction, the cam 71 will raise one end portion of the lever 73 and thereby move the opposite lug or foot 75 into working position. This operation is repeated when the head 54 substantially reaches its limit of movement in the opposite direction. In view of the foregoing, it will be readily seen that the desired reciprocation of the piston 51 is obtained by continuous rotation 85 of the member or drum D in one direction. 90

The outer longitudinal marginal portion of the table T is provided therealong with a groove or channel 85 in which is arranged for endwise sliding movement an elongated bar 86 provided at one end portion with the racks 87 meshing with the gears 88 carried by the spindles 89 of the lower rotary valves 90. 95

Each of the valves 90 is tubular and is 100 arranged within an enlarged portion 91 of either the head 33 or head 92 of the cylinder C and one end of said valve 90 is open. The open end portion of the valve 90 extends within the reservoir or tank R and coacting with said inserted or open end is a flat valve 93 which serves to normally maintain said inserted or open end of the valve 90 closed. 105

Each of the valves 90 is also provided with an elongated slot or port 94 which, when the valve 90 is in one position, registers with the port 95 in the adjacent wall of the cylinder or chamber C so that the air as compressed within the cylinder or chamber C by the piston 51 will be delivered 110 within the tank or reservoir R. 115

In the present embodiment of my invention, each of the valves 90 constitutes a lower valve and the gear 88 coacting with said valve 90 meshes with the gear 96 carried by the stem 97 of an upper rotary valve 98. Each of the valves 98 is seated within the enlarged portion 91 of the cylinder or chamber C and said valve 98 has disposed therethrough a port 99 which, when in one position, affords communication between the atmosphere and the interior of the cylinder or chamber C through the ports 100, so that when the piston 51 is compressing air at one side thereof a supply of air is being drawn 120 into the cylinder or chamber C at the oppo- 125

site side of the piston 51 for the compression of the reverse or return stroke.

The elongated member or bar 86 operates to properly adjust the valves 90 and 98 in 5 timed sequence and the requisite movement of the member or bar 86 is transmitted from the head 54.

The end portion of the member or bar 86 remote from the cylinder or chamber C is 10 provided therethrough with the openings 101 in which are mounted the idle gears *a*, *b* and *c* supported by the side walls of the member 86 defining the openings 101 and which gears *a*, *b* and *c* are adapted to coact 15 with the relatively short racks 102 produced on the base or bottom of the groove or channel 85 hereinbefore referred to.

Extending outwardly and laterally from the head 54 at substantially its center is a 20 flat extension or plate 103 terminating in an angular portion 104 providing a downwardly facing groove or channel 105 in which the upper portion of the member or bar 86 is received. The base portion of the 25 groove 105 is provided therealong with the rack 106.

Pivottally engaged with the opposite extremities of the angular portion 104 of the extension or plate 103 and having swinging 30 movement toward or from the member or bar 86 are the substantially U-shaped members 107 having their base portions outwardly disposed and the base or intermediate portion 108 of each of the members 107 35 is provided with a depending tooth 109 for a purpose to be hereinafter more particularly referred to.

The pivoted end portions of the outer side arms of the members 107 are provided 40 with the depending rock arms 110 with their lower or free end portions connected by the rigid link 111, whereby the members 107 are caused to swing in unison but in reverse directions. The arms 110 are in such angular 45 relation that when one of the members 107 is in lowered or working position, the second member 107 is in a raised or inoperative position.

As illustrated in Figures 3 and 9, the piston 51 together with the head 54 are at the 50 limit of their outward movement and at which time the outer member 107 has been swung downwardly as particularly illustrated in Figure 9 by contact of an end of 55 the link 111 with a depending lug 112 carried by the table T. As the member or drum D rotates, the head 54 will be caused to move toward the cylinder or chamber C with the resultant stroke of the piston 51. The outer member 107 when lowered engages the outer gear *a* which is in mesh with the outer rack 102 so that as the head 54 travels, movement 60 will be imparted to the member or bar 86. Just before the member 107 or more particularly 65 the tooth 109 thereof passes from the

gear *a*, the rack 106 carried by the angular portion 104 of the extension or plate 103 will engage the gear *b*.

At the time the rack 106 engages the gear *b*, said gear *b* is in a position to mesh with the intermediate rack 102 so that as the head 54 continues to travel toward the cylinder or chamber C, the bar or member 86 will be continued to move. When the head 54 is at the limit of its inward movement, the gear *c* 70 will be in mesh with the inner rack 102 at substantially the same position the gear *a* occupies in Figure 9 with the gear *b* inwardly of the intermediate rack 102. Just before the head 54 reaches the limit of its 75 inward movement, the inner end of the link 111 contacts with the inner depending lug 112 carried by the table T whereby the inner member 108 is lowered to engage the gear *c* and the outer member 107 raised into 80 an inoperative position, so that upon the return or outward movement of the head 54, the operation just described will be repeated and the bar or member 86 moved outwardly. The movement of the bar or member 86 in 85 either direction is sufficient to cause the racks 87 thereof to rotate the valves 90 and 98 from one position to the other in proper timed sequence.

113 denotes a safety valve of any preferred construction coacting with the reservoir or tank R and which automatically opens when the pressure of the air within the tank or reservoir R passes a predetermined degree.

From the foregoing description it is thought to be obvious that a compressor constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the character described including a compressor comprising a cylinder, a piston mounted therein for rectilinear movement, a rod engaged with the piston and extending exteriorly of the cylinder, a head carried by the extended portion of the rod and travelling in a substantially fixed path of travel, a lever pivotally supported substantially midway its length by the head, a cylindrical member rotatably supported adjacent the head, said member being provided in its periphery with spiral channels disposed in opposite directions from substantially the center thereof, the merging 115 120 125 130

portions of said channels being raised to provide a lifting cam, one end portion of the lever being engaged within a spiral groove when the opposite end portion is positioned free, the cam coacting to reverse the position of the lever, and means for rotating the rotary member.

2. A device of the character described including a compression cylinder provided with an intake port and an exhaust port, rotary valves controlling said ports, one of said valves being in opened position when the second valve is in closed position, meshing gears carried by said valves whereby the same rotate in unison, a piston arranged

within the cylinder for rectilinear movement, a rod operatively engaged therewith and extending exteriorly of the cylinder, an elongated member supported for endwise movement and provided with a rack meshing with the gear of one of the valves whereby reciprocation of said member moves the valves from one position to the other, and coacting means carried by the rod and the member for imparting the requisite movement to the member.

In testimony whereof I hereunto affix my signature.

WILLIAM J. KREIMER.
